RACKET

Theophilus A. Davis, Los Angeles, Calif.

Application March 30, 1936, Serial No. 71,553

7 Claims. (Cl. 273—73)

This invention relates generally to tennis rackets and the like, and more particularly to methods of and means for controlling the weight and balance of tennis rackets.

In the manufacture of rackets, the final total weight and balance of course is kept constantly in view during the making of the frame. It is well known, however, that it is impracticable to attempt to control weight and balance simply by shaping and selection of wood densities. Accordingly, it has been the practice in the art that the final total weight of a racket, as well as its balance, are controlled by a selected mass placed in a selected and adjustable position in the handle. Thus, for instance, it has been common to put a lead plug in the handle, or to drive into the end of the handle a suitable number of pins of suitable length and to drive them in to a suitable position. Such methods, however, are not entirely effective in compensating for the factor of varying handle sizes, and the consequent variation of the total weight and balance.

It is accordingly a primary object of the present invention to provide a tennis racket construction in which weight and balance can be controlled with increased effectiveness in the making of rackets of various handle sizes.

A preferred form of racket to which the invention is particularly adaptable involves a frame and handle made up of several continuous laminations which extend completely around the head and into the handle. The outermost laminations are extended to the butt end of the handle, the interior laminations being stopped at a distance of some six inches from that end. The space between these outermost laminations at the butt end of the handle is filled with a plug of very light wood, such as balsa wood, with its grain running transversely, so that the end grain of the balsa wood is presented to the inner surfaces of the outside laminations.

The final desired total weight of the frame is controlled as closely as possible by selection of wood densities. For example, batches of wood of relatively light density are employed in making up frames in the lighter weights, and vice versa. Compensation necessary to be made to take care of varying handle sizes, and of final balance, are provided for by varying the size of the balsa wood filler. For example, everything else being equal, and it being desired to make up a racket having a small size handle, a somewhat smaller balsa filler is put in and the two outside handle laminations pressed in against it. Accordingly, it being the light balsa filler that is changed in dimension

to provide for the smaller handle, rather than the heavier wood of the handle laminations, the total weight of the handle is not greatly decreased, but is kept up to the value required for correct racket balance. On the other hand, if a large handle is desired, a somewhat larger than average balsa filler is inserted, and thus the total weight of the finished handle is kept down to the point required to maintain substantially the same finished balance.

For purposes of further adjustment, the length of the light balsa filler may be varied so as to provide more or less weight of heavy wood in the handle.

With this preliminary discussion, the invention will now be more fully understood by referring to the drawings, and to the following detailed description of a present preferred embodiment of the invention.

In the drawings:

Fig. 1 is an elevation of a tennis racket of a type to which the present invention may be applied;

Fig. 2 is a side elevation of the handle of the racket shown in Fig. 1;

Fig. 3 is a view similar to Fig. 1, but showing the racket with the throat laminations removed and with part of the handle broken away to expose the construction of the handle in accordance with the present invention;

Fig. 4 is a view similar to a portion of Fig. 3, showing a handle of relatively smaller size in accordance with the invention;

Fig. 5 is a view showing the handle in a large size form;

Fig. 6 is a section taken on line 6—6 of Fig. 4;

Fig. 7 is a section taken on line 7—7 of Fig. 5; and

Fig. 8 shows the handle in an intermediate stage of manufacture.

The racket here shown for illustrative purposes comprises the usual oval head 10 and handle 11, the head being formed of a plurality of wood plies in oval formation converging at the lower end toward throat 14 and thence, except for certain plies which are cut out to permit insertion of the relatively light wood filler (to be described), continuing downwardly to form the handle. The several plies are formed to the desired shape of the frame by placing them in a press, the contacting surfaces of the plies having been previously coated with an adhesive, and the frame is then allowed to remain in the press a length of time suitable for the adhesive to dry and the

plies to become securely glued together to form a rigid frame.

The head portion of the frame includes four relatively thicker plies 15, 16, 17, and 18 which extend around the head, and extend downwardly beyond the throat to form the handle. There are also two relatively thinner plies 20 and 21 placed between the thicker plies as shown. The racket also has, within the triangular space at the throat, a block 25 shaped in accordance with the curvatures of the frame sides at this point, and a pair of laminations 26 and 27 are glued on the upper side of the block and to the inside of the frame, tapering out as shown.

15 Added to the four major plies making up the frame and handle is a fifth ply 28, which begins with a taper just above the throat and extends downwardly into the handle, as shown in Fig. 3.

To strengthen the frame at the throat, thin 20 plates 35 of wood veneer are glued to opposite faces of the frame at the throat. These veneer plates extend for a short distance toward the handle and up along each side of the head, as shown in Fig. 1. In the embodiment here illustrated, each of these plates 35 is made up of two plies 35a and 35b.

The racket as now described is simply typical of a type of racket to which the present invention may advantageously be applied; it is to be understood, however, that the improvements of the present invention are not necessarily limited to certain details of the racket here chosen for illustrative purposes.

Referring now to the handle construction of 35 the racket, it will be seen from Fig. 3 that the two outermost plies 18 and 28 continue to the butt end of the handle, while plies 15, 16, 17, 20, and 21 stop at a point about midway of the handle, say six to eight inches from its butt end, as indicated in Figs. 3, 4, and 5.

The frame members as so far described are made of relatively dense and heavy wood, such as ash, walnut, birch, hickory, etc.

The space between outermost handle plies 18 45 and 28 and below the lower ends of the short plies 15, 16, and 17 is filled with a plug 38 of some relatively light wood, as balsa wood, placed with its grain running transversely, that is, with its end grain presented to the inner surfaces of the 50 two outsides edge strips 18, 28.

The racket handle is built out at the sides to proper size and weight by means of side slabs or plates 40, which are glued to the edges of the handle plies and to the side surfaces of balsa 55 wood plug 38, these side members extending upwardly from the butt end of the handle, and their upper ends tapering out at a point several inches below the throat, as illustrated. The outer surfaces of side plates 40 and exterior handle 60 plies 18 are finally cut to the conventional octagonal tennis racket handle shape, as illustrated in Figs. 6 and 7.

The butt end of the handle is finished by placing a rubber or leather cap 42 over the end and 65 securing it to the wood. Before this is done, however, it may be found desirable to insert one or two or more metal pins 43 into the butt end of the racket to effect a final balance adjustment (Fig. 3).

70 In making up the frame as thus described, the properly cut plies are coated with glue and placed in the press, with the balsa plug 38 placed in position, and an extra ply 45, which extends the length of the handle, is placed and glued on 75 the outer surface of each outside ply 18, as il-

lustrated in Fig. 7. The press is then set up to press the plies tightly together, and the glue allowed to dry and set.

The handle is next sawed to the proper width dimension, which operation may remove all or 5 nearly all of the added plies 45. In the instance of Fig. 3, the plies 45 are shown as having been entirely removed by the sawing operation. In Fig. 5, a thin fragment of the plies 45 is illustrated as remaining. This sawing operation is accurately carried out with reference to the center line of the head of the racket, so that the handle will finally be symmetrical with reference to this center line. If in the gluing operation the handle has become offset slightly from this center line, the sawing operation may remove a slight amount of the wood of the handle ply 18 on one side while leaving a corresponding thickness of the extra ply 45 on the other. The use of the added plies 45 and the sawing operation as 10 described thus assures that the final handle will be accurately symmetrical with reference to the center line of the head of the racket. Where the handle as originally formed is symmetrical and accurately centered with reference to the center line of the head, however, the entirety of the plies 45 may be removed, or an equal thickness of these plies may be left on each edge of the frame (Fig. 5).

Fig. 3 is illustrative of an average size racket 30 handle, in which is used a balsa plug 38 of a thickness t equal to the original dimension between the two outside or edge strips 18, 28. When the freshly glued racket frame is placed in the press and the press is tightened, the inner surfaces of members 28 are tightly pressed against the exposed end grain of the balsa wood block. There is accordingly no tendency for the balsa wood to be crushed. If the grain of the balsa wood were to run longitudinally of the 35 handle, on the other hand, the pressure of the press would cause this balsa wood block to crush and the handle frame to fracture or break down at once. It is therefore essential that the grain of block 38 run at right angles to the inner 40 surfaces of side plies 28, and this constitutes a feature of importance in the present invention.

If now a racket frame is to be made up with a handle size smaller than on the racket of Fig. 3, a balsa wood block of slightly less thickness t' is 50 used.

Accordingly, when this handle is placed in the press, the two outermost plies 18, 28 below the lower ends of plies 15, 16, 17 becomes squeezed inwardly until they engage the end grain surfaces 38a of block 38', this condition being illustrated clearly in Fig. 4. It will now be evident that when the racket handle as so formed is then subsequently sawed down to the size required, a lesser amount of heavy wood of the outermost 60 plies 18 will be removed than had the plies not been squeezed inwardly into engagement with the reduced dimension block 38'. Thus, a relatively larger amount of the heavy wood of the handle (the outside plies) is preserved than had the handle of the racket of Fig. 3, with a balsa wood block of thickness dimension t , been sawed down to the reduced dimension required. The amount of light wood lost to the handle by reducing the dimension of the balsa block from 65 thickness t to thickness t' has an immeasurable effect on the weight of the handle. Thus by this manner of construction, the weight of the handle is kept well up while its width dimension is reduced.

Likewise, if a racket handle of relatively larger size is required, a balsa wood block 38' of increased thickness dimension t'' (Fig. 5) is chosen, causing plies 18 and 28 to be flexed outwardly a corresponding amount. When the edges of the handle are then sawed to the larger dimension required, in this instance, the ultimate result will again be that substantially the same amount of the relatively heavy wood is used in the handle. In this instance, therefore, the weight of the handle has been kept down to average by flexing plies 18 and 28 outwardly, and filling the extra space by using a thicker balsa wood block, so that again the quantity of the relatively heavy wood in the handle remains substantially unchanged.

It will thus be evident that the total thickness of the four heavy wood layers made up of plies 18 and 28 remains substantially the same in the three handle sizes, the three handles differing mainly in the differing thicknesses of the balsa wood filler employed. And because of the relative lightness of this balsa wood filler, such variation in thickness from handle to handle causes very little difference in the weight or balance of the three rackets.

The immediately foregoing description is based on the assumption that the thickness dimension t (distance between plies 28) is constant, as it usually will be in rackets made up of plies of the same thicknesses. However, in the practical manufacture of rackets, different ply-woods are used, of slightly differing densities; and consequently the plies are a little different in thickness in order that the total weights remain about the same. For instance plies of walnut will be a little thicker than those of ash; and in a racket made of the former wood the dimension t will be somewhat larger than in a racket made of ash. To obtain the same size of handle in each instance, a balsa block 38 of the same size is used; resulting in that the walnut handle plies may be bent inwardly as in Fig. 4, while the ash plies may be bent out as in Fig. 5. The construction consequently will be seen to take care of varying ply thicknesses, while at the same time maintaining desired handle sizes.

A further variable condition is encountered in the fact that in order to maintain the conventional geometrical cross sectional shape of the handle constant, the side plates or slabs 40 are made relatively thinner as the handle size becomes smaller, and relatively thicker as the handle size becomes greater, tending to diminish the weight of the handle for the smaller handle sizes, and to increase the weight of the handle for the larger handle sizes. This variation is usually compensated, however, since the smaller handle sizes are usually demanded with the lighter weight rackets; the fact that the side plates 40 for such lighter and relatively small handled rackets are relatively thinner and therefore of relatively lighter weight is therefore usually of advantage rather than a disadvantage, tending as it does to hold the balance of the racket constant rather than to cause unbalance. A corresponding result in the other direction obtains with the heavier and relatively larger handled rackets.

However, if it is desired to make up a racket of small handle size but of relatively heavy weight, then the length of the balsa plug may be reduced, and the relatively heavy plies 15, 16, and 17 extended further down into the handle. This will have the effect of increasing the weight

of the handle to compensate the lessened weight due to the thinner side plates or slabs that go with the smaller handle. Fig. 4 is illustrative of such an adjustment, the plug 38' being illustrated as being somewhat shorter in length than the plug 38 of the racket of Fig. 3.

Correspondingly, a racket handle of large size (Fig. 5) may be kept down in weight by increasing the length of the balsa plug, and therefore decreasing the quantity of the heavy wood in the handle.

As a variational means of compensating for the increased weight of the handle due to thicker side plates 40 in the larger handle sizes, the inner surfaces of such plates 40 may be routed out or grooved, as indicated at 48 in Figs. 5 and 7.

Preferably, I construct the rackets to be slightly light in the handle, if anything, so that final adjustment for balance can be made by driving one or two short metal pins 43 in the butt end 20 of the handle. This final adjustment is all that is required to balance the racket for the trade after it has been glued together, trimmed, and finished.

Thus it will be seen that my racket construction enables the size of the handles to be varied during manufacture without substantial change in the quantity of the relatively heavy wood in the handle, so that rackets of different handle sizes will all balance about alike. Since the 30 lighter rackets (constructed usually of lighter samples of wood) are usually provided with the smaller handle sizes, any lightening of the handle due to use of thinner side plates 40 is a compensatory change as regards racket balance, as is use 35 of thicker side plates on the larger size handles. But when a racket of large sized handle but light weight, or a racket of small size handle but heavy weight, is wanted, this may be taken care of by control of the longitudinal length of the balsa plug, and therefore of the quantity of relatively heavy wood in the handle, which varies inversely with the length of the balsa plug. Or, in the instance of the few extremely large size handles, this condition may be taken care of by 45 routing the inner surfaces of the side plates.

It will be evident that the provisions of the present invention are adaptable to rackets of many different types of construction. It is essential, however, that the rackets to which the provisions of the present invention are to be applied include two somewhat flexible members running down the two opposite edges of the handle, such as are capable of being flexed inwardly or outwardly to conform to the thickness of the 55 balsa plug to be used in any given instance. In the present illustrated racket, these side members are made up of two glued together plies 18 and 28. It will be evident, however, that the use of two such plies is not limitative on the invention, the requirement being simply that two flexible members be provided capable of being bent inwardly or outwardly as the thickness dimension of the light wood plug or filler may be varied.

I claim:

1. In a tennis racket handle, the combination of two outside substantially flat flexible edge members of relatively heavy wood extending parallel to one another the length of the handle, relatively heavy wood material between said edge members extending from the racket throat end of the handle to a point about midway of the length of the handle, a relatively light wood filler block between and abutting the inner surfaces of said 75

edge members and extending from a point near the lower end of said wood material to the butt end of the handle, the grain of said filler block running at right angles to the flexible edge members, the thickness of said block measured in the direction of the grain being less than the distance between the flexible edge members at the upper end of the handle, and said flexible edge members being flexed inwardly at the upper end of 10 said filler block and being glued against its adjacent end grain surfaces.

2. In a tennis racket handle, the combination of two outside substantially flat flexible edge members of relatively heavy wood extending 15 parallel to one another the length of the handle, relatively heavy wood material between said edge members extending from the racket throat end of the handle to a point about midway of the length of the handle, a relatively light wood filler 20 block between and abutting the inner surfaces of said edge members and extending from a point near the lower end of said wood material to the butt end of the handle, the grain of said filler block running at right angles to the flexible edge 25 members, the thickness of said block measured in the direction of the grain being greater than the distance between the flexible edge members at the upper end of the handle, and said flexible edge members being flexed outwardly at the upper 30 end of said filler block to accommodate the increased thickness thereof.

3. In a tennis racket handle, the combination of two outside substantially flat flexible edge members of relatively heavy wood extending 35 parallel to one another the length of the handle, relatively heavy wood material between said edge members extending from the racket throat end of the handle to a point about midway of the length of the handle, a relatively light wood filler 40 block between and abutting the inner surfaces of said edge members and extending from a point near the lower end of said wood material to the butt end of the handle, the grain of said filler block running at right angles to the flexible edge 45 members, the thickness of said block measured in the direction of the grain being greater than the distance between the flexible edge members at the upper end of the handle, and said flexible edge members being flexed outwardly at the upper 50 end of said filler block to accommodate the increased thickness thereof, and side plate handle members fastened against the edges of said flexible members and to said relatively heavy wood material, said side plate members being grooved on their 55 inner surfaces to reduce their weight.

4. In a tennis racket handle, the combination of two outside substantially flat flexible edge members of relatively heavy wood extending parallel to one another the length of the handle, 60 interior plies of relatively heavy wood extending downwardly in the handle between said edge members to a point about midway of the length of the handle, and a relatively light wood filler block between and abutting the inner surfaces of said 65 edge members and extending from a point near the lower ends of the interior plies to the butt

end of the handle, the thickness of said block measured at right angles to the planes of the edge members being slightly less than the total thickness of the interior plies, and said flexible edge members being flexed inwardly at the upper 5 end of said filler block against the adjacent surfaces of said block.

5. In a tennis racket handle, the combination of two outside substantially flat flexible edge members of relatively heavy wood extending parallel 10 to one another the length of the handle, interior plies of relatively heavy wood extending downwardly in the handle between said edge members to a point about midway of the length of the handle, and a relatively light wood filler block 15 between and abutting the inner surfaces of said edge members and extending from a point near the lower ends of the interior plies to the butt end of the handle, the thickness of said block measured at right angles to the planes of the edge 20 members being slightly greater than the total thickness of the interior plies, and said flexible edge members being flexed outwardly at the upper end of said filler block to accommodate the increased thickness thereof. 25

6. In a tennis racket handle, the combination of two outside substantially flat flexible edge members of relatively heavy wood extending parallel to one another the length of the handle, relatively heavy wood material between said edge 30 members extending from the racket throat end of the handle to a point about midway of the length of the handle, a relatively light wood filler block between and abutting the inner surfaces of said edge members and extending from a point 35 near the lower end of said wood material to the butt end of the handle, the grain of said filler block running at right angles to the flexible edge members, the thickness of said block measured in the direction of the grain differing slightly 40 from the distance between the flexible edge members at the upper end of the handle, and said flexible edge members being flexed at the upper end of said filler block to accommodate such dimensional difference. 45

7. In a tennis racket handle, the combination of two outside substantially flat flexible edge members of relatively heavy wood extending parallel to one another the length of the handle, interior plies of relatively heavy wood extending downwardly in the handle between said edge members to a point about midway of the length of the handle, and a relatively light wood filler block 50 between and abutting the inner surfaces of said edge members and extending from a point near the lower ends of the interior plies to the butt end of the handle, the thickness of said block measured at right angles to the planes of the edge members being slightly different from the total thickness of the interior plies, and said flexible 55 edge members being flexed at the junction between said interior plies and said filler block to accommodate such difference in thickness between the interior plies and the filler block. 60
